UNITED STATES PATENT OFFICE.

CHARLES M. BRANDT, OF TOLEDO, OHIO, ASSIGNOR TO HIMSELF, HARRY R. BACON, HORATIO A. BLACK, AND FRANK M. LONG, ALL OF SAME PLACE.

ADJUSTABLE SHAFT-HANGER.

SPECIFICATION forming part of Letters Patent No. 414,489, dated November 5, 1889.

Application filed January 29, 1889. Serial No. 297,991. (No model.)

To all whom it may concern:

Be it known that I, CHARLES M. BRANDT, a citizen of the United States, residing at Toledo, in the county of Lucas and State of Ohio, have invented certain new and useful Improvements in Adjustable Shaft-Hangers; and I do hereby declare that the following is a full, clear, and exact description of the invention, which will enable others skilled in the art to which it appertains to make and use the same, reference being had to the accompanying drawings, and to the letters of reference marked thereon, which form part of this specification.

My invention relates to adjustable shaft-hangers, and has for its object to provide a shaft-hanger with a positive and easily-manipulated adjustment with which to line a main shaft when out of line. A further object is economy of construction and to provide a hanger (either single or duplex) that can be adjusted without the aid of skilled labor.

The invention consists in the parts and combination of parts hereinafter described, and pointed out in the claims.

In illustrating my invention I have shown a single hanger adjustable by means of a rack-bar and pinion, and also a duplex hanger actuated by the same adjustment, the advantage of the same being a quick and positive means of lining a shaft.

In the drawings, Figure 1 is a side elevation of a standard with a portion of the same broken away to disclose the rack-bar and pinion. Fig. 2 is a like view showing the squared axis by which the pinion is revolved, and also a pawl-and-ratchet mechanism by which the suspension-bar is held to any desired adjustment. Fig. 3 is a side elevation of a duplex hanger, a portion of the hanger being broken away to disclose the two rack-bars and the intermediate pinion for actuating the same. Figs. 4 and 5 are views in cross-section on the lines *x x* and *y y*, respectively, of Figs. 2 and 3, the two last-named figures being intended to show the dovetailed arrangement of the rack-bars within the dovetailed grooves of the hanger.

A designates the shaft journaled in bearings B, pivotally secured to the suspension-bars C by set-screws or bolts D, in the usual manner. Suspension-bars C are each formed with a toothed portion, the teeth D'' of the same being upon one side of each suspension-bar, said sides being dovetailed in form longitudinally to fit within dovetailed recesses E of hangers F, which are provided with any preferred means of attachment to joists G. Within the hangers F are placed pinions H, mounted upon shafts I, said shafts being journaled in the hangers, and of a length to project through the same upon the front side a sufficient distance to receive a ratchet-wheel K and allow a wrench or crank to be secured upon the free end to turn the same, and with the shaft the pinion by which to raise or lower the suspension-bar.

L designates a pawl engaging with ratchet-wheel K to hold the pinion in fixed position whenever the suspension-bar is properly adjusted.

From the above description the operation will be easily understood. The shaft being secured in place within bearings B, the suspension-bars C are placed within the dovetailed recesses E of the hangers, the rack-bar thereof engaging with the pinions within the hangers. Shafts I are now turned by means of a wrench or crank placed upon the projecting end thereof, and the pinion of each hanger is turned to raise or lower the suspension-bar, as may be requisite to line the shaft.

In Fig. 3 is shown a duplex hanger, in which each rack-bar works in dovetailed recesses in hanger F, with the shaft A running longitudinally of the suspension-bars, the bearings B for the shaft being pivotally secured in the same at some distance from the hanger, the suspension-bars being at right angles to the rack-bars and extending parallel with the shaft at any desired distance, and is then bent at right angles to the toothed portion D'' and bifurcated to receive bearings B. In this construction the operation is essentially the same. The revolution of the pinion H, however, tends to raise one of the suspension-bars and depress the opposite one to the same

extent, this construction being of practical value where great tension is required upon the belt and where the pulley is placed upon the shaft intermediate two suspension-bars. The 5 shaft can thus be readily adjusted by raising one of the suspension-bars and depressing the opposite one.

What I claim is—

1. A shaft-hanger comprising a hanger 10 formed with a recess to receive a suspension-bar, and a pinion journaled in the hanger, in combination with a suspension-bar formed with a toothed portion adapted to be moved within the recess when the pinion is revolved, 15 as and for the purpose set forth.
2. In a shaft-hanger, a hanger, a pinion jour-

naled therein upon an axis having a squared outer end, a ratchet-wheel upon the axis, and a pawl secured to the hanger and engaging with the ratchet-wheel, in combination with 20 one or more toothed suspension-bars movably secured to the hanger and held in engagement with the pinion, as and for the purpose set forth.

In testimony that I claim the foregoing as 25 my own I hereby affix my signature in presence of two witnesses.

CHARLES M. BRANDT.
